UNITED STATES PATENT OFFICE.

HERBERT S. JANDUS AND JOHN RICHARD MORGAN, OF DETROIT, MICHIGAN, AS
SIGNORS TO THE C. G. SPRING & BUMPER COMPANY, OF DETROIT, MICHIGAN, A
CORPORATION OF DELAWARE.

DESIGN FOR A CLAMP PLATE FOR VEHICLE BUMPERS.

Application filed September 9, 1927. Serial No. 23,343. Term of patent 14 years.

To all whom it may concern:

Be it known that we, HERBERT S. JANDUS and JOHN RICHARD MORGAN, citizens of the United States, residing at Detroit, in the county of Wayne and State of Michigan, have invented a new, original, and ornamental Design for a Clamp Plate for Vehicle Bumpers, of which the following is a specification, reference being had to the accompanying drawing, forming part hereof,

wherein Fig. 1 represents a front elevation and Fig. 2 a side elevation of a clamp plate for vehicle bumpers exhibiting our new design.

We claim:

The ornamental design for a clamp plate for vehicle bumpers, substantially as shown.

HERBERT S. JANDUS.
JOHN RICHARD MORGAN.
